UNITED STATES PATENT OFFICE.

LORENZ KILLIAN, OF BROOKLYN, NEW YORK, ASSIGNOR TO PALMER & EMBURY MFG. CO., OF NEW YORK, N. Y., A CORPORATION OF NEW JERSEY.

DESIGN FOR A CHAIR.

40,469.

Specification for Design.

Patented Jan. 25, 1910.

Application filed November 13, 1909. Serial No. 527,962. Term of patent 7 years.

To all whom it may concern:

Be it known that I, LORENZ KILLIAN, a citizen of the United States, residing at Brooklyn, in the county of Kings and State of New York, have invented a new, original, and ornamental Design for Chairs; and I do hereby declare the following to be a full, clear, and exact description of the same, reference being had to the accompanying drawing, forming a part thereof.

The design comprises the general outline of a chair together with the ornamental carving of the legs, the back uprights, curv-

ing and merging into each other centrally, the curved arms merging into the front legs, the open lattice work arrangement connecting the back upright having arranged therein a cane lattice work.

I claim:—

The ornamental design for a chair as shown and described.

LORENZ KILLIAN.
